UNITED STATES PATENT OFFICE

ERICH LOENING, OF BERLIN-WILMERSDORF, GERMANY

PROCESS FOR PRODUCING ROTOGRAVURE MOUNTING FORMS

Application filed October 28, 1926, Serial No. 144,912, and in Germany October 31, 1925.

This invention relates to processes for producing rotogravure mounting forms and aims to provide an improved method of producing such forms.

5 The production of rotogravure printing cylinders according to present methods takes considerable time and a quicker process has been sought for several years.

To the lengthy methods still in general use, there are two especially great objections, viz:

10 First. The type and illustration (full line and half tone) must be separately mounted, exposed, transferred, coated and etched, and these steps of mounting, exposing, transferring, coating and etching must therefore be done twice.

15 Second. The bordering of the illustrations on the printing cylinder and the covering of all parts which are not to be etched is a difficult and lengthy procedure.

20 The attainment of quicker and better results has been sought by first printing the text and illustration on white paper and mounting both parts on white cardboard from which a negative was made and from which latter a diapositive was taken. The parts of this diapositive containing the text were covered with an asphalt lacquer while particular care was exercised not to cover parts thereof containing the illustrations. The uncovered parts of the diapositive were ther dyed by a non-actinic dye and the lacquer was thereafter washed off, so that the 25 diapositive was produced containing the text part on a highly transparent ground whereas the transparency of the parts containing the illustrations was more or less reduced by a non-actinic dye.

25 This method was complicated and it was found most difficult and troublesome to apply the asphalt lacquer to parts of the whole surface free from pictures. Moreover, the removal of the lacquer was objectionable and after several photographic steps the sharpness of text and pictures was found to be noticeably reduced.

30 In distinction over the known methods, the present invention provides a method for producing a mounting form for rotogravure

which contains type and illustration at the same time, which allows the simultaneous exposing, transferring and etching of type and illustration, and also secures perfect results without bordering and covering the 55 pictures.

This effect is obtained by at first producing diapositives on films, the transparency of which has already been reduced during the manufacturing process. Films may be used 60 wherein either the celluloid substance, or the front or back side thereof has been slightly colored (especially with an inactinic color), or wherein a specially colored layer has been applied thereto.

65 After drying, the diapositives produced on such films are cut to the required size and stuck onto the mounting glass in the desired arrangement and at the desired place.

70 The type is printed on transparent material (e. g. the so-called cellophane) in the usual way and inserted and fixed between the pictures.

75 According to this method, a mounting is obtained which is transparent throughout with the exception of the type and illustration. The type and illustration are then transferred together onto the copper cylinder which need be coated only at such places which show the plain copper and this may be done very easily and quickly. The type and illustration are then etched together and at the same time.

80 The invention will now be particularly described with reference to the accompanying drawings wherein diagrammatic representations are made by way of example.

85 In said drawings:

Fig. 1 shows a sheet of paper to be printed in part with text and in part with illustrations;

Fig. 2 shows a mounting plate on which only the text containing parts have been fixed;

Fig. 3 shows the separately prepared parts containing the pictures.

Fig. 4 is a sectional representation taken on the line IV—IV through one of the illustration-containing parts of Fig. 3;

Fig. 5 is a view similar to Fig. 2, but con-

taining the prepared illustration parts introduced between the text containing parts; and Fig. 6 is a section taken on the line VI—VI of Fig. 5.

5 In a very diagrammatic manner, Fig. 1 shows a sheet of paper 1 being imprinted in part with types and in part with illustrations. The text-containing parts are denoted by the rectangles 2, 3, 4 in broken outline 13 within which the type is represented by horizontal zig-zag lines. Between said text-containing parts, other rectangles 5, 6 and 7 are shown in full lines representing half-tone illustrations therewithin, the pictures being 15 indicated by irregular patch lines.

According to this invention, the text part or type is printed on fully transparent film or thin sheet material, such for example as so-called cellophane sheets and the printed text 20 is then cut into pieces 2', 3', 4' corresponding in size to the parts 2, 3, and 4 of Fig. 1, and these parts are then fixed upon a mounting plate 8 in any known manner.

Diapositives of the illustrative parts 5, 6 25 and 7 are separately produced on films by ordinary photographic methods. These film parts 5', 6' and 7', corresponding in size to the parts 5, 6 and 7 of Fig. 1, are made less transparent, being coloured in any desired 30 manner, especially by means of a non-actinic colour. In the illustrated example, it may be understood that the film substance (see Fig. 4) is prepared from a material which is slightly coloured in its body or substance and 35 bears upon the side the usual gelatin layers or emulsion containing the picture P (see Fig. 4).

The covering of these parts 5', 6' and 7' 40 is represented in Fig. 3 by a slight cross-hatching of the corresponding rectangles. The diapositive rectangles 5', 6', 7' prepared in this manner are now fixed upon the mounting plate 8 in proper relation to the parts 2', 3' and 4' as shown in Fig. 5 and in this manner 45 a mounting is obtained from which the text and pictures can be directly transferred to the copper cylinder in the usual manner which needs no further description or illustration.

50 Having thus described my invention, what I claim as new and desire to secure by Letters Patent of the United States is:

1. The method of producing rotogravure 55 mounting forms for printing of type with illustrations from photographic films, which consists in printing the type on transparent material and separately preparing and coloring the photographic films of illustrations with an inactinic color, and then applying the 60 transparent material bearing the type and the colored films bearing the illustrations onto a mounting glass in the desired relation.

2. The method of producing rotogravure 65 mounting forms including type and illustration cuts, which consists in printing the type

in non-transparent color on sections of transparent material, separately preparing diapositives of the illustrations upon photographic films of reduced transparency and coloring the same with an inactinic color, and then fixing the sections of material bearing the type and the colored films bearing the illustrations in the desired relation upon a mounting plate.

3. The method of producing rotogravure 70 mounting forms embodying type and illustration cuts, which consists in printing the type in ordinary non-transparent color on sections of transparent material, separately preparing diapositives of the illustrations upon photographic films the transparency of which is reduced by means of a layer of non-actinic colour, and then fixing the sections of material bearing the type and the films bearing the illustrations in the desired relation 75 upon a mounting plate for transfer to a copper cylinder.

In testimony whereof I have affixed my signature.

DR. ERICH LOENING.
